UNITED STATES PATENT OFFICE.

ERNEST H. KORSMEYER, OF KANSAS CITY, MISSOURI, ASSIGNOR TO THE KANSAS CITY HAY PRESS COMPANY, A CORPORATION OF MISSOURI.

GOVERNING AND VALVE-OPERATING MECHANISM FOR GAS OR VAPOR ENGINES.

SPECIFICATION forming part of Letters Patent No. 708,485, dated September 2, 1902.

Application filed April 29, 1901. Serial No. 57,971. (No model.)

To all whom it may concern:

Be it known that I, ERNEST H. KORSMEYER, a citizen of the United States of America, residing at Kansas City, in the county of Jackson and State of Missouri, have invented certain new and useful Improvements in Governing and Valve-Operating Mechanism for Gas or Vapor Engines; and I do hereby declare that the following is a full, clear, and exact description of the invention, such as will enable others to make and use the same, reference being had to the accompanying drawings, forming a part of this specification.

The object of my invention, primarily, is to open the exhaust-valve in a gas-engine at each alternate stroke of the piston after each explosion of the gas and control its speed and cause the spark ignition only when necessary; second, to regulate the speed of the engine.

The invention consists in the novel construction and combination of parts, such as will be first fully described, and specifically pointed out in the claims.

In the drawings, Figure 1 is a side view of the cylinder of a gas or vapor engine, showing the exhaust-valve and the improved valve-controlling mechanism and igniter, also showing the main driving-shaft in section and the eccentric and eccentric-rod operating the valve mechanism. Fig. 2 is a transverse sectional view taken upon the line $x-x$ of Fig. 1, also showing the base-frame supporting the cylinder of the engine and the rock-shaft. Fig. 3 is a plan view in detail of the valve-operating mechanism with the eccentric-rod removed. Figs. 4 and 5 are side views in detail of the operating mechanism of the valve-igniter, showing the positions of the operative parts when acting to open and close the exhaust-valve, respectively, the latter figure showing the igniter in connection with the valve-operating mechanism. Fig. 6 is a side view, enlarged, of the igniter; and Fig. 7 is a plan view of the same. Fig. 8 is a detail view in perspective of the main or governor-supporting plate or casting broken away to show the plunger, &c., and the tripper for the igniter, the rotary alternating cam, the hook on the reciprocating plate, the notched bar on the forward end of the rear

supporting-plate, and the cam-actuating pawl. Fig. 9 is a view in detail of the opposite side of the notched sliding bar operating the lever in the rock-shaft, showing the cam-actuating pawl. Fig. 10 is a rear view of the cam. Fig. 11 is a detail view in perspective of the box on the main frame, showing the vibrating bar and speed-regulating device. Fig. 12 is a detail view of the end of the igniting-chamber on the cylinder of the engine.

Similar letters of reference indicate corresponding parts in all the figures of the drawings.

Referring to the drawings, A represents the hollow cylinder of a gas or vapor engine in which the energy is obtained from repeated explosions of gas mixed with air in the well-known manner. Said cylinder is supported by a horizontal base-plate a , which is integral with the cylinder and arranged in position a short distance above the level of the ground. With each side of said base-plate are connected the upwardly-extended side supporting-plates a' a' , the upper ends of which side plates are bent inwardly at right angles, and secured to the base-plate by the bolts a^2 and nuts a^3 a^4 . a^5 is the water-jacket upon the outer side of and shown extending about two-thirds the distance around the cylinder A. Through the lower portion of the cylinder A at a point equidistant from its ends is an exhaust-opening a^5 , which also extends through the base-plate a . Extending from the exhaust-opening a^5 in a transverse direction to the cylinder is a chamber a^6 for the suction of air in the igniter-cylinder, herein-after described, the bottom a^8 of which chamber is depressed a short distance below the plane of the upper side of the base-plate a . The outer end of the chamber a^6 , which extends a short distance beyond the line of the outer side of the water-jacket a^4 , is enclosed by a lateral extension or casting a^9 , extending from the cylinder A and integral therewith through the water-jacket a^4 and a short distance therefrom, forming the upper side of said chamber a^6 , and a vertical end plate a^{10} , extending upwardly from the bottom a^8 of the said chamber to the outer end of the casting a^9 , in the upper portion of

which end plate a^{10} is a circular opening a^{12} for the reception of the cylinder or casting of the igniter, hereinafter described.

B represents the casing for the exhaust-valve, which consists of an annular box b slightly larger in circumference than the exhaust-opening a^5 and having a bottom b' and a chamber b^2 . In the top of the said box is a circular opening b^3 for the valve, the sides of which opening are inclined. In the opening b^3 is seated a valve b^4 . Through the side of the box b extends an opening b^5 . With the bottom b' of box b is connected a downwardly-extended annular casing b^6 , the sides of which are inclined inwardly toward the lower end. In the bottom b' of the box b is an opening b^7 , through which extends the upper end of a valve-stem b^8 , which also extends through valve b^4 and is secured to the said valve by the nut b^9 . The lower end of the valve-stem extends downwardly within the casing b^6 and a considerable distance below the lower end of said casing and is screw-threaded, and upon said screw-threaded end is fitted a nut b^{10} . Extending downwardly from the under side of said nut are forked portions b^{12} . Extending around the stem b^8 and between the lower end of the casing b^6 and the nut b^{10} is a spiral spring b^{14} . The upper end of the box b abuts against the under side of the bottom a^8 of the chamber a^6 upon one side and the annular flange a^{14} , which extends downwardly an equal distance from the under side of base a , upon the under side of the opening a^5 , as shown in Fig. 2, and which extends around the opening a^5 to said bottom a^8 . Said box b is retained in position by the horizontally-extended flanges b^{15} , extending from the sides of said box, as shown in Fig. 1. With the under side of base a are connected the upper ends of the rods $b^{16} b^{16}$, the lower ends of which rods are screw-threaded and extend through the flanges b^{15} , and upon said rods beneath said flanges are nuts $b^{17} b^{17}$.

C represents the operating mechanism for the engine, which consists of a longitudinally-extended bracket-stand c , which is arranged near the side of the water-jacket a^4 in a vertical position and in a parallel plane with the outer face of the end a^{10} to the chamber a^6 . Extending from the ends of bracket c downwardly are supports or standards $c' c'$, which rest upon the upper side of the base-plate a of cylinder A, and upon the lower ends of said supports are the lateral or foot supports $c^2 c^2$, which are bolted to the base-plate a by the bolts a^2 , which pass through said flanges and also secure the base a to the upright base-supporting plates $a' a'$. The inner edges $c^x c^x$ of the supports $c' c'$ are curved inwardly in the arcs of circles to admit the face-plate upon the igniter-cylinder, hereinafter described. At the rear end of plate c and extending laterally from the upper and lower edges of said plate a short distance from its outer face are the guide-flanges $c^3 c^3$, the outer

ends of which flanges are bent at right angles and extended toward each other a short distance, forming thereby a guide box or bearing in which reciprocates the main or governor-supporting plate D. The forward end of the guide-box extends about one-third the distance toward the forward end of said plate c , and the main reciprocating plate D is equal in length to about one-half the length of said plate c . Said main plate consists of a hollow casting, (shown in detail in Fig. 8,) through the rear end of which extends transversely one end of a stud-shaft d , the other end of which shaft d extends through the outer side of the plate D between the inner edges of the sides of the flanges $c^3 c^3$, which form the boxing for said plate, and a short distance beyond the outer side of said flanges. 85

E represents the main driving-shaft of the engine, which is shown in section in Fig. 1, and upon which is an eccentric-plate e , around which extends the ring e' , made in two parts and secured together by the bolts e^2 and nuts e^3 . With the ring e' is connected one end of an eccentric-rod e^4 , the other end of which rod extends to the stud-shaft d on the reciprocating plate D and is pivotally connected therewith. 95

Within the hollow casting or plate D is a movable plunger-bar F, one end of which bar is pivotally connected with the stud-shaft d . The other end of said bar extends a considerable distance beyond the forward end of plate D or so far as to contact with the valve-operating slide-bolt, hereinafter described, when actuated at the proper time. The forward end d^x of the hollow casting or plate D, extending a short distance downwardly from the plane of its top, is curved rearwardly, as seen in Fig. 8. In the forward end of said bottom portion of the hollow casting or plate D is a longitudinal opening d^2 .

Upon the under side of the portion of plunger-bar F within the hollow casting D is a tripping-plate f , which extends downwardly through the opening d^2 in the bottom of the hollow casting or plate D and a short distance below the plane of the under side of said plate and which engages with the gas-igniting devices, hereinafter described, the lower end from the forward side being curved or inclined, as at f' . The upper edge of the main supporting plate or stand c , extending from an intermediate point upon said edge to the forward end of plate c , is cut away on a plane a short distance below the plane of the top flange c^3 of the boxing for the sliding plate D. Upon the outer side of said forward end of plate c is a roller casting or box G, which extends rearwardly a short distance and in which is the longitudinal opening g , which extends part way in width toward the plate c , and near said plate c the upper and lower sides are contracted in width, as at g' in Fig. 11. Within the opening g is a sliding bar H, in the outer side of which bar, at its forward end, is a pin h , which enters a notch h' in the

outer side of the boxing G and limits the play of the bar H rearwardly. In the rear end and under side portion of the bar H is a notch h^2 . Upon the inner side of bar H and within the 5 opening g' in the box G is a pawl I, which consists of a narrow plate, upon one side and end of which is a pivot i , which enters a perforation h^3 in the inner side of said plate, (see Fig. 3,) located at a point about equidistant 10 from the ends of bar H. The outer end of said pawl is curved downwardly in a slight degree and is obliquely inclined at the extreme outer end.

In the inner side of bar H is a pin i^2 , which 15 is located near the pivot i on pawl I in the direction of the forward end of bar H. Around the pin i^2 is a spiral spring i^3 , one extended end portion i^4 of which extends to the side of pawl I and is bent at right angles and inserted 20 ed within said pawl. The other end of said spring extends in an opposite direction and is bent at right angles and extended within the side of the bar H. Between the upper side of the plunger-bar F and the inner side 25 of the top of the hollow casting or plate D is a spiral spring f^4 .

In the outer side of the main supporting-plate c in a vertical line with the forward support c' to said plate and below the plane ex-30 tended from the under side of box G is a stud k^0 , upon which is a triangular-shaped cam K, having three faces $k k k$, upon which the outer end of plunger-bar F contacts. Upon the outer side of the cam K are separate pins k' 35 $k' k'$, located near the angles formed by the respective sides of the cam. Upon the inner side of cam K is a ring k^2 , upon the outer surfaces of which, at a point intermediate the line of the angles formed by the respective 40 sides of said cam, are alternating cam-teeth k^3 and which are formed by lines extending longitudinally to said ring, as seen in Fig. 10, and with which cam-teeth the pawl I alternately engages. The outer end of the stud-45 shaft k is screw-threaded, and upon said end is a screw-threaded cap k^4 . Extending around the stud-shaft k , between the cap k^4 and the cam K, is a spiral spring k^5 , the tension of which is regulated by the cap k^4 .

50 In the outer side of the hollow casting or plate D, at its forward end, is a longitudinal opening d^3 , which is upon one side of the plunger-bar F, and in which opening is pivoted at d^4 to the outer side of the plate D one end of 55 a vibrating barbed stem L, upon the outer end of which stem is a hook or barb l, the forward end of which hook is rearwardly inclined, as at l', and which hook extends to and engages with the pins $k' k' k'$ on the cam K 60 alternately. Between the upper side of the stem of hook L and the upper side of the opening d^3 is a spiral spring l^3 .

Upon the upper side of the box G is the speed-regulating device M, which consists of 65 a vibrating plate m, pivotally connected at one end to the lugs $g^2 g^2$ on the forward end of the said box, the other end of which plate

extends rearwardly a considerable distance beyond the vertical plane of the rear end of box G or so far as to be met by the extended 70 arm upon the governor, hereinafter described, and upon the under side of said end is a downward extension or hook m' , which is located a short distance from the rear end of box G, on the lower inner side of which hook is a 75 slight inward projection or lip m^2 . In the rear end of the sliding bar H and near the upper side of said bar is a transverse groove h^4 , with which the lip m^2 on plate m is made to engage at the proper time. 80

On the top of box G, near the rear end, are lugs $n n$, extending upwardly a short distance, upon the upper ends of which is secured by screws $n' n'$ the transverse plate N. With the vibrating plate m is connected one end 85 of a rod n^4 , the other end of which rod extends upwardly through an opening n^5 in plate N and a considerable distance above said plate. The upper end of rod n^4 is screw-threaded, and upon said end is a nut n^6 and 90 a lock-nut n^7 . Extending around the rod n^4 , between the nut n^6 and the plate N, is a spiral spring n^8 . On the rod n^4 , between plates m and N, is a washer or cushion n^2 .

O represents the governor, which consists 95 of a vibrating standard o, the lower end of which standard extends within an opening o' in the upper side and near the forward end of the reciprocating plate D, as seen in Fig. 8, and is secured therein by the pivot o^2 . 100 With the standard o, a short distance above the top of the plate D, is connected one end of an arm o^3 , the other end of which arm extends to a position above the upper side and rear end of the vibrating plate m, the forward 105 end of said arm being bent downwardly at an angle and extended nearly to the said plate. Upon the upper end of standard o is a weight o^6 . Between the arm o^3 and the top of the hollow casting or plate D is a spiral spring o^4 . 110 Upon the other side of the standard o and extending in an opposite direction to arm o^3 is a short arm o^5 , the outer end of which is bent at right angles and extended downwardly 115 nearly to the upper side of plate D. 115

P represents the gas-igniting device, which consists of a front plate p, the ends of which are formed in arcs of circles and of the proper dimensions to extend within the curved inner edges $c^x c^x$ of the supports $c' c'$ to the main 120 supporting plate or stand c and contact with the outer end a^9 of the chamber a^6 . Through the ends of plate p are openings p' , (see Fig. 6,) in which are inserted the screw-bolts p^2 , which extend within the screw-threaded openings a^{14} in the lugs a^{13} on each side of the end a^{10} to the chamber a^6 , as seen in Fig. 12. With the inner side of plate p is connected a cylinder p^3 , which extends through the opening a^{12} in the end a^{10} of the chamber a^6 and 130 within the upper part of said igniter-chamber and nearly to the inner side of cylinder A. Through the plate p and longitudinally through the cylinder p^3 extends an opening

p^4 , which is located above a transverse line extending through the center of the cylinder and in which opening is a rock-shaft p^5 , the ends of which extend a short distance beyond the outer side of plate p and the inner end of the cylinder p^3 , respectively. Upon the outer end of shaft p^5 , near the plate p , is an upwardly-extended arm p^6 , which is perforated transversely. Upon the inner end of shaft p^5 is an arm p^7 . In the outer end of the arm p^7 is a transverse opening p^8 , in which is inserted a copper or non-corrosive-metal bushing p^9 , the ends of the opening p^8 being reamed, so as to permit of the outward-flaring ends of the bushing. The inner sides of the bushing p^9 are circular in cross-section, in which bushing is forced a contact-pin p^{10} , which is rectangular in cross-section. Through the plate p and longitudinally through the cylinder p^3 extends a stationary tapering pin q , insulated from the cylinder p^3 by suitable insulation, the ends of which extend a short distance beyond the face-plate p and the inner end of the cylinder p^3 , respectively. The outer end of pin q forms a binding-post for an electric wire, in which is a transverse opening q' for the end of one of the wires from a suitable battery, (not shown,) the other wire being contacted with the cylinder p^3 or the engine. In the end of pin q is a screw q^2 for securing said wire in the binding-post. On the inner end of pin q is a contact point or pin q^4 , which is the same as pin p^{10} and contacts with the pin p^{10} on the arm p^7 of the rock-shaft p^5 . On the outer side of plate p , near the bottom of said plate and also toward the forward end of said plate, is a stud-bolt r , upon which is pivoted one end of a flat plate r' , the upper end of which plate extends the height of the arm p^6 on shaft p^5 and is slightly curved upon its rear side. Through the upper end of plate r' extends one end of a bolt r^2 , which is screw-threaded at both ends. The other end of bolt r^2 extends loosely through the opening in the arm p^6 on shaft p^5 . Upon one end of bolt r^2 is a nut r^3 , which bears against the forward side of the plate r' , and upon the other end of said bolt is a nut r^4 , which bears against the rear side of the arm p^6 . Extending around shaft p^5 , between the arm p^6 and the plate p , is a spiral spring p^{12} , one end p^{13} of which extends to a position on the forward side of the arm p^6 and is extended part way around said arm. The other end of said spring is connected with a pin p^{14} on the outer side and with the rear end of said plate. With the pivoted plate r' is connected a bolt r^5 at a point a short distance below the rod r^2 . With the bolt r^5 is connected one end of a spiral spring r^6 , the other end of which spring is connected with a pin r^7 , inserted in the front side of the forward support c' to plate c , a short distance below the stud k , supporting the cam K .

Upon the inner side of the vertical supports a' to the base a , as seen in Fig. 2, are shaft-

bearings s , (see Fig. 2,) on which are journaled the opposite ends of a rock-shaft S , which is beneath the forward end of cylinder A . Upon said shaft are oppositely-extended lever-arms $s' s^2$. Beneath the arms $s' s^2$ is a horizontal beam s^3 , one end of which beam extends to a position beneath the nut b^{10} on the exhaust-valve B and between the forked extensions $b^{12} b^{12}$ of said nut. With the beam s^3 , at a point intermediate its ends, is connected pivotally a link s^4 , the other end of which link is connected pivotally with the outer end of arms s' on shaft S . In the outer end of arm s^2 is an opening s^5 , in which is inserted the upper screw-threaded end of a rod s^6 , upon which rod, beneath the under side of said crank, is a nut s^7 . In the outer end of the beam s^3 , beneath said rod s^6 , is a cup-shaped bearing s^8 , in which the lower end of rod s^6 is inserted. With the end of rock-shaft S which is toward the side of support a' upon which the valve-operating mechanism is located is connected one end of a lever T , the outer end of which lever contacts with the outer end of the sliding bar H in the box G on the forward end of plate c . In the bottom a^8 of the chamber a^6 , beneath the cylinder A , is a valve-opening u , with which is connected upon the under side of said bottom a^8 an air-valve U , which is precisely the same in construction as the exhaust-valve B , the spiral spring u' to said valve U being weaker than the spring b^{14} of the exhaust-valve B .

In operation power is communicated to the main shaft E , which is an ordinary crank-shaft of the engine operated by pistons in the cylinder (not shown) in the well-known manner from the successive explosions of gas in the cylinder A , and which is generated by an admixture of air which is drawn through the valve-opening u upon the opening of the valve U to the chamber a^6 . Any kind of a gas-making device may be connected with valve U . The rotation imparted to shaft E communicates a rotary movement to the eccentric e and also a reciprocating movement to the rod e^4 , which is also imparted to the plate D . As the reciprocating plate D moves forward in its initial stroke, the position of the cam K being in the position as seen in full line on Fig. 5 or that of the plunger F , bears upon one of the sides of the cam, the forward end of the plunger will pass beneath the rear end of the sliding bar H . Upon the said forward movement of the reciprocating plate D the action of the pistons in the cylinder takes in sufficient air through the valve U to mix with the vaporized gasoline or gas in the cylinder in readiness for the explosion. Upon the partial rearward movement of the plunger-bar F the pistons compress the gas, and in full rearward movement to the position, as seen in Fig. 4, the tripping-plate f meets the upper end of the vibrating plate r' , which moves forwardly under the tension of the opening r^6 and releasing its control of the bolt r^2 and moves upon said bolt sufficiently to permit

the action of the spring p^{12} , the end p^{13} of which throws the upper end of the arm p^6 on the rock-shaft p^5 rearwardly, which actuates said shaft and draws the pin p^{10} into contact 5 with pin q^4 within the cylinder A. In the same rearward movement described of plate D the hook l engages with one of the pins k' on the cam K and partially rotates said cam and also elevates the plunger F, which then 10 bears upon one of the angles of said cam, the tripper-plate f on said plunger-bar releases the pivoted plate r' , which instantly moves forward to its normal position under the tension of the spring r^6 and contacts with the 15 nut r^3 , drawing the arm p^6 on the shaft p^5 and throwing the contact-points $p^{10} q^4$ away from each other, and the said contacts being in an electric circuit produce a spark. The air and gas being then under compression, the 20 spark ignites the gas and an explosion follows, the result energizing the shaft E. Following the explosion of gas the plate D again moves forward the plunger-plate, which being elevated by the angle of cam K strikes 25 the sliding bar H, moving said bar forward, also vibrates the lever T, causing a partial rotation of the rock-shaft S, which action raises the arm s' upwardly and forces up the valve-stem b^8 , lifting the exhaust-valve b^4 , which 30 exhausts the burned gases from cylinder A, and the cylinder is prepared for another charge of air and gas. In the backward movement of the plate D the spring b^{14} of the exhaust-valve B raises the forward end of beam 35 s^3 , causing a partial rotation of shaft S in an opposite direction and causing the upper end of lever T to throw the slide-bar H in the direction of the plate D into a position for the action of the plunger-bar, the rearward movement 40 of bar H being checked by the pin h upon reaching the notch h' in the box G. In said rearward movement of bar H the pawl I meets one of the teeth k^3 on the rear side of cam K, causing a partial rotation of said cam 45 and lowering the forward end of the plunger-bar F in a position to miss the sliding bar H in the next forward movement of plate D. Thus it will be observed that in each forward-and-backward movement of plate D the action 50 of the hook L and the pawl I causes a partial rotation alternately of cam K, and the plunger-bar F alternately strikes the sliding bar H and enters the notch h^2 in the rear end of said bar and respectively operating 55 the exhaust-valve to free the burned gases in the forward movement of plate D and tripping the igniter in a partial rearward movement of said plate until a certain degree of speed of the governor will throw down or lock 60 the plate m and prevent a rearward movement of the slide-bar H. As the speed of the engine increases and its movement causes the plate D to reciprocate at a rapid pace the vibration of the governor O causes the arm o^3 to contact 65 with the vibrating plate m with sufficient force to throw the end of said plate downwardly, and at the moment the slide has moved forward to

open the exhaust-valve the projection or lip m^2 on said hooked portion m' of the vibrating bar enters the notch h^4 in the rear end of bar H, 70 and the bar is locked or retained from movement and the exhaust-valve kept in an open position until such time that the speed of the engine decreases and the vibrations of the governor are lessened and the power of spring n^8 on the rod n^4 overcomes the engagement of the lip m^2 with the sliding bar H, when the vibrating bar raises in position and releases said bar for contact with the plunger-bar F and at the same time closes the exhaust-valve b^4 . In order to increase the speed of the engine, the nut n^6 is turned upon rod n^4 , so as to increase the tension of spring n^8 , which action requires a stronger vibration of the arm o^3 of the governor to actuate the vibrating plate m and retard the action of the sliding plate H, as seen in Fig. 5. When the tension of spring n^8 is adjusted, the lock-nut n^7 retains the nut n^6 from movement. The successive stages of action in a gas-engine are 80 thus under intimate control and economizing the power which ordinarily is spent in unnecessary explosion of gas. The beam s^3 , being suspended by the link s^4 and adjustably balanced by the rod s^6 , enables the valve-stem b^8 of the exhaust-valve B to be moved upwardly in position to raise the valve without binding or being moved laterally when the rock-shaft S is given a partial rotation, it being observed that the adjusting of the nut s^7 on the rod s^6 will change the position of beam s^3 at an angle to the arms $s' s^2$ on the rock-shaft S. In order to control the action of cam K, the tension is regulated by the cap k^4 on stud-shaft k. 85 90 95 100 105

It is obvious that instead of making the reciprocating plate D in the form of a hollow casting it may be of one thickness intermediate the top and bottom and the rod e^4 and plunger F connected with the respective outer and inner sides of the plate.

Such other modifications may be employed as are within the scope of the invention.

Having fully described my invention, what I now claim as new, and desire to secure by Letters Patent, is—

1. In valve-operating mechanism, the combination with the exhaust-valve, of a spring-retracted, slideable bar, a valve-actuating reciprocating plate, a plunger pivotally connected with said plate and coacting with and actuating intermittently the slideable bar, a rotatable cam supporting the outer end of said plunger and adapted to remove said plunger from contact with said slideable bar, and coacting devices upon said reciprocating plate and said slideable bar imparting motion alternately to said cam, in the reciprocal movements of the said plate and slideable bar. 120 125 130
2. In valve-operating mechanism, the combination with the exhaust-valve, of a spring-retracted, slideable bar, a valve-actuating reciprocating plate a plunger pivotally connected with said plate, coacting with and actu-

- ating intermittently the slidable bar, a rotatable cam supporting the outer end of said plunger, and adapted to move the outer end of said plunger from contact with the slidable bar, a self-engaging barbed stem pivotally connected with the said reciprocating plate, and a pawl upon the slidable bar, and devices upon each side of said cam actuated alternately by said barbed stem and said pawl.
5. In valve-operating mechanism, the combination with the exhaust-valve, of a spring-retracted, slidable bar actuating said valve, a reciprocating plate, a plunger pivotally connected with said plate and actuating the slid- 70
able bar, a rotatable cam supporting the outer end of said plunger pins upon one side of said cam, and teeth upon the other side in alternate, transverse positions to said pins, a stem pivotally connected with said reciprocating 75
plate and a barb at the outer end engaging automatically with said pins, and a pawl upon the slidable bar engaging with said teeth in the reciprocal movements of said plate and sliding bar.
10. 3. In valve-operating mechanism, the combination with the exhaust-valve, of a spring-retracted, slidable bar actuating said valve, a reciprocating plate, a plunger pivotally connected with said plate and actuating the slid- 80
able bar, a rotatable cam supporting the outer end of said plunger pins upon one side of said cam, and teeth upon the other side in alternate, transverse positions to said pins, a stem pivotally connected with said reciprocating 85
plate and a barb at the outer end engaging automatically with said pins, and a pawl upon the slidable bar engaging with said teeth in the reciprocal movements of said plate and sliding bar.
15. 4. In valve-operating mechanism, the combination with a suitable supporting bracket or stand and with the exhaust-valve, of a spring-retracted, slidable bar actuating said valve, suitable guides upon said stand there- 90
for, a reciprocating plate, and guides upon said bracket therefor, a spring-actuated plunger coacting with and actuating the slidable bar, and pivotally connected with said plate, a stud-shaft upon said bracket, and a rotatable cam upon said stud-shaft supporting the outer end of said plunger, and adapted to move said plunger from contact with the slid- 95
able bar, pins extending from one side of said cam, and teeth upon the other side in alternate, transverse position to the pins, a spring-actuated stem pivotally connected with the reciprocating plate, and self-engaging devices upon said stem adapted to engage with the pins on said cam, and a spring-actuated pawl 100
pivotally connected with the slidable valve-operating bar and arranged to engage with the teeth on said cam, and a spring on the stud-shaft bearing against said cam.
20. 5. In valve-operating mechanism, the combination with the exhaust-valve and with a suitable supporting bracket or stand of a guide-box at one end thereof, a spring-retracted slidable bar in said box, guide-bearings at the other end of said bracket, and a reciprocating plate on said bearings and a plunger pivotally connected with said plate and coacting to actuate said slidable bar, a spring-actuated pawl pivotally connected with said sliding bar, a stud-shaft upon said 105
bracket, and a rotatable cam upon the stud-shaft supporting the outer end of said plunger and adapted to move the outer end of said plunger in and out of contact with the slid- 110
able bar, pins extending outwardly from one side of said cam, and a ring upon the other side, and teeth upon said ring in alternate, 115
transverse positions to the said pins, adapted to be engaged by the pawl on the sliding bar, and a stem pivotally connected with the reciprocating plate, and a hook upon said stem having a rearwardly-inclined forward end.
25. 6. In a vapor-engine, the combination with the main power-shaft and the exhaust-valve, of a valve governing and operating mechanism comprising a reciprocating plate, and a supporting-bracket therefor, and guide-bearings upon said bracket, a vibrating governor, upon said reciprocating plate, and vibrating arms upon said governor, an eccentric upon the power-shaft and an eccentric-rod connect- 120
ed with the eccentric and also connected with the reciprocating plate, a spring-retracted, slidable bar operating the exhaust-valve and a spring-actuated locking-plate arranged above said slidable bar and engaging intermittently therewith, and also actuated intermittently by one of the arms of the governor, a spring-actuated plunger-bar pivotally connected with said reciprocating plate and co-acting intermittently with the slidable bar, a 125
cam supporting the outer end of said plunger and pins upon and extending outwardly from one side of said cam and teeth upon the other side in alternate, transverse position to said pins, and adapted to be engaged alternately by said pawl, and a spring-actuated stem pivotally connected with said reciprocating plate, and a barb upon said stem engaging alternately with said pins.
30. 7. In a valve operating and governing mechanism for vapor-engines, the combination with the exhaust-valve and a spring-retracted valve-operating slidable bar, and with a guide-box therefor of a reciprocating plate, a spring-actuated plunger-bar pivotally connected with said plate and coacting intermittently with said slidable bar, a vibrating plate pivotally connected at its forward end with the forward end of said box, and a hook thereon, and a lip upon said hook, said slid- 130
able bar having a transverse groove adapted to receive said lip, lugs upon the rear end of said guide-box for said sliding bar, and a transverse plate upon said lugs, a rod connected with the rear end of the vibrating plate having its upper end screw-threaded and extending through the said transverse plate on said lugs, an adjusting-nut upon said rod, a spiral spring upon said rod between said nut and said transverse plate, and means for moving said hooked end of said vibrating plate into engagement with said slidable bar.
35. 8. In vapor-engines, the combination with the cylinder of the engine, having an air and gas mixing chamber, of an exhaust-valve, a cylinder for the gas-igniting devices connected with the cylinders of the engine, and a cylinder-plate, a crank-shaft and an insulated pin within said igniter-cylinder, and contacts on the inner ends of said shaft and pin, a spring holding said contacts normally apart, a plate pivotally connected at one end with

the cylinder-plate for the gas-igniting devices, a spring retracting said pivoted plate, a rod extending through said plate and the crank in the crank-shaft of the igniting devices, 5 nuts upon the ends of said rod, a reciprocating plate, a plunger pivotally connected with said plate, devices actuated by said plunger and opening said exhaust-valve intermittently, and a tripper upon the said plunger 10 actuating said pivoted plate on the cylinder-plate intermittently.

9. In vapor-engines, the combination with the cylinder of the engine having an air and gas mixing chamber, of an exhaust-valve, a 15 cylinder for the gas-igniting devices connected with the cylinder of the engine and a cylinder-plate, a crank-shaft and a stationary, insulated pin extending through said igniter-cylinder, contacts upon the inner ends of 20 said shaft and pin and a spring holding said contacts normally apart, a spring-retracted plate pivotally connected with the cylinder-plate, a rod extending through said plate and the crank-arm on the crank-shaft, adjusting- 25 nuts on the ends of said rod, a bracket upon the engine and suitable guides at one end of said bracket, a plate in said guides, a plunger pivotally connected with said plate, means for reciprocating said plate, a box at the other 30 end of said bracket, a slideable valve-actuating bar in said box actuated intermittently by said plunger, a rotatable cam upon said bracket supporting the outer end of said plunger, devices upon said reciprocating plate 35 and said slideable bar actuating said cam alternately, and a tripping-plate on said plunger actuating said pivoted plate on the cylinder-plate for the igniting devices intermittently.

10. In valve-operating devices for gas-engines the combination with a spring-actuated exhaust-valve, of a rock-shaft, arms upon said shaft, an adjustable balanced beam upon said arms actuating said valve and means for operating said rock-shaft.

45. 11. The combination with a spring-actuated exhaust-valve, of a rock-shaft, arms upon said shaft, a beam having its rear end extending to and actuating said valve, a link connecting said beam intermediate its ends 50 with one of said arms on the rock-shaft, a rod connected adjustably with the other arm and bearing upon the outer end of said beam, a lever on the rock-shaft and means for actuating said lever, substantially as described.

55. 12. The combination in a vapor-engine with the cylinder and its base and with the side supports for said base of a rock-shaft, a spring-actuated exhaust-valve, slideable valve-operating mechanism upon said base of the engine-cylinder, and a lever on the rock-shaft contacting therewith, arms upon said rock-shaft, a beam having one end extending to and operating the exhaust-valve, a link connected with one arm of the lever and with the 60 said beam intermediate its ends and a screw-threaded adjusting-rod connected with the other arm having one end of said rod bearing

upon the outer end of said beam, and an adjusting-nut on said rod beneath said arm.

13. In vapor-engines, the combination with 70 the cylinder of the engine and its main driving-shaft, of an eccentric upon said shaft, and an eccentric-rod, a spring-actuated exhaust-valve on said cylinder, a bracket upon said engine, a reciprocating plate upon said 75 bracket, and suitable guides upon said bracket therefor, a stud-shaft upon said plate with which said eccentric-rod is connected, a plunger pivotally connected with said plate, a triangular-faced cam on said bracket supporting the outer end of said plunger, pins upon the outer side and near the angles of said cam, and teeth upon the other side of said cam in alternate, transverse position to the said pins, a stem pivotally connected with 80 said reciprocating plate, and a hook on said stem having a rearwardly-inclined forward end, a slideable bar in said bracket, actuated intermittently by said plunger, a box on said bracket therefor and a spring-actuated pawl 85 pivotally connected with the inner side of said slideable bar, engaging with the teeth on the inner side of said cam, and gas-igniting devices upon the said engine actuated intermittently by said plunger.

95. 14. In vapor-engines, the combination with the cylinder of the engine and its main driving-shaft, of an eccentric upon said shaft and an eccentric-rod, a spring-actuated exhaust-valve in said cylinder, a bracket upon said engine, a reciprocating plate upon said 100 bracket, and suitable guides therefor, and a stud-shaft on said plate, with which said eccentric-rod is connected, a spring-actuated plunger pivotally connected with said plate, 105 a stud-shaft on said bracket, and a rotatable, triangular-faced cam on said stud-shaft supporting the outer end of said plunger, a spring bearing on said cam, pins upon the outer side of and near the angles of said cam, teeth 110 upon the other side of said cam in alternate, transverse position to said pins, a stem pivotally connected with said reciprocating plate, and a hook having a rearwardly-inclined, forward end engaging alternately with said pins, 115 a guide-box upon the other end of said bracket, a slideable valve-actuating bar in said box, intermittently acted upon by said plunger, a spring-actuated pawl engaging alternately 120 with the teeth on said cam, a rock-shaft upon said engine, and arms upon said shaft, a beam having its inner end engaging with the exhaust-valve, a link connecting one of said arms on the rock-shaft with said beam, intermediate the ends thereof, a rod adjustably 125 connected with the other arm and bearing on the forward end of said beam, and a lever on the rock-shaft, having its free end contacting with the forward end of the sliding bar, substantially as described.
